CLAIM

The ornamental design for a container for confectionary products, as shown and described.

DESCRIPTION

FIG. 1 is a front elevational view of a container for confectionary products showing my new design;

FIG. 2 is a rear elevational view thereof, the vail being shown in an alternate position;

FIG. 3 is a left side elevational view thereof, the undisclosed opposite side being a mirror image;

FIG. 4 is an exploded rear perspective view thereof, the vail being shown as disclosed in FIG. 2; and,

FIG. 5 is an exploded front perspective view of FIG. 4, the vail being shown as disclosed in FIG. 1.
